DESIGN FOR A HANDBAG

Jacob Scala, Brooklyn, N. Y.

Application April 5, 1939, Serial No. 84,055

Term of patent 3½ years

To all whom it may concern:

Be it known that I, Jacob Scala, a citizen of the United States and resident of Brooklyn, in the county of Kings, in the State of New York, have invented a new, original, and ornamental Design for a Handbag, of which the following is a specification, reference being had to the accompanying drawing, forming a part thereof.

Figure 1 is a front elevational view, Figure 2 is a top plan view, and Figure 3 is a bottom plan view of a handbag, showing my design.

I claim:

The ornamental design for a handbag, as shown.

JACOB SCALA.
